(57) **CLAIM**

The ornamental design for a carbide paint scraper, as shown and described.

DESCRIPTION

FIG. 1 is a front, top perspective view of a carbide paint scraper showing our new design;

FIG. 2 is a rear top perspective view from the rear thereof;

FIG. 3 is a left side elevational view thereof;

FIG. 4 is a right side elevational view thereof;

FIG. 5 is a top plan view thereof;

FIG. 6 is a front elevational view thereof;

FIG. 7 is a rear elevational view thereof;

FIG. 8 is a bottom plan view thereof;

FIG. 9 is a front top perspective view thereof, with its rotating knob shown in an alternate position;

FIG. 10 is a top perspective view thereof, with its rotating knob shown separately from the base for clarity of disclosure;

FIG. 11 is a front top perspective view of a second embodiment of a carbide paint scraper showing our new design;

FIG. 12 is a rear top perspective view thereof;

FIG. 13 is a left side elevational view thereof;

FIG. 14 is a right side elevational view thereof;

FIG. 15 is a top plan view thereof;

FIG. 16 is a front elevational view thereof;

FIG. 17 is a rear elevational view thereof;

FIG. 18 is a bottom plan view thereof;

FIG. 19 is a top perspective view thereof, with its rotating knob shown in an alternate position; and,

FIG. 20 is a top perspective view thereof, with its rotating knob shown separately from the base for clarity of disclosure.
